UNITED STATES PATENT OFFICE.

CLARENCE H. YOUNG, OF BOSTON, MASSACHUSETTS.

SKID.

Application filed February 27, 1923. Serial No. 621,588.

My invention relates to skids and particularly but not exclusively to that type known as "live" skids.

My invention which has among its objects 5 the provision of a durable construction which may be fabricated and readily repaired with a minimum of expense and labor will be best understood from the following description when read in the light of the 10 accompanying drawings showing the preferred embodiment of my invention selected for illustrative purposes, while the scope of my invention will be more particularly pointed out in the appended claims.

15 In the drawings:—

Fig. 1 shows a plan view of the skid with parts broken away;

Fig. 2 shows a bottom view of part of the framing for a skid; and

20 Figs. 3, 4, 5 and 6 are sections on the lines 3—3, 4—4, 5—5 and 6—6 of Fig. 1.

Referring to the drawings and to the preferred embodiment of my invention I have shown at each side of the skid a girder which 25 includes the spaced longitudinally arranged angle-irons 1 and 3 which as shown in the drawings are placed with one web horizontally positioned and with the horizontal web of one angle-iron extending towards the 30 horizontal web of the other.

For holding the girders at opposite sides of the skid and likewise the angle-irons 1 and 3 included in each girder in spaced relation I provide the cross members herein exemplified by the angle-irons 4, 5, 6 and 7, 35 these angle-irons being positioned above the angle-irons 1 and 3 with one of their webs placed vertically and with the horizontal web of each in contact with the horizontal webs of the angle-irons 1 and 3 and riveted 40 or otherwise secured thereto as is indicated at 9 in the drawings.

If desired each girder may and preferably does comprise a third angle-iron 11 which in 45 the assembled skid forms in conjunction with the angle-iron 1 one structural member. As clearly illustrated in the drawings the angle-irons 11 rest upon and are positioned similarly to the angle-irons 1 being held in desired relation therewith by means of the 50 tubular spacers 13 interposed between the horizontal webs of the respective angle-irons. For holding the angle-irons 1 and 11 in assembled relation I provide bolts 15 which 55 extend through perforations in the horizon-

tal webs of the angle-irons and through the tubular spacers 13.

The flooring for the skid comprises the transversely arranged planks 17 the ends of which are received in the channel shaped recesses between the horizontal webs of the angle-irons 1 and 11. These planks lie in side to side relation with the vertical webs of the angle-irons 4, 5, 6 and 7 which vertical webs divide the planks into two groups and retain the planks against movement longitudinally of the skid. It will be noted by this construction that the girders and the members forming the girders are held in spaced relation independently of the planks 60 17 and consequently that these planks which must be renewed from time to time need not be formed with such exactness as if the planks were depended upon for spacing the girders. It will be further noted that my 65 construction permits the planks which preferably fit the framing rather loosely to move relatively to each other and to the girders when the skid is loaded without distorting or putting undue strains on the remaining 70 structural elements of the skid. Renewal of the bolts 15 which permits detachment of the angle-irons 11.

In the drawings I have indicated the skid 75 as provided with rear wheels 19 and front wheels 21, the latter as will be understood by those skilled in the art being carried in swivelled relation to a caster base 23.

For providing supports for the caster bases 23 for the front wheels 21 of the skid I rivet or otherwise connect to the angle-irons 1 and 3 near the front ends thereof a pair of brackets 25 the vertical webs of which are shown at 27 as riveted to the vertical 80 webs of the angle-irons 1 and 3 and the horizontal webs of which are perforated to receive the bolts 29, the latter being provided for securing the caster bases to said horizontal webs. For giving rigidity to the supports for the caster bases and to the girders I mount on the upper sides of the horizontal webs of the brackets 25 short sections of angle-irons 31 which bridge the pairs of brackets 25 near opposite ends thereof. The bolts 29 hereinbefore referred to likewise extend through the angle-irons 31 and hold the same in assembled position.

The wheels 19 for the rear end of the skid are supported in bearing blocks 33 secured 100 105 110

to the under side of the horizontal webs of angle-brackets 35 by means of stud bolts 36, the vertical webs of the angle-brackets 35 being riveted or otherwise secured as is indicated at 37 to the vertical webs of the angle-irons 3. For reenforcing the girders adjacent the wheels 19 each vertical web of the angle-irons 1 and 3 has riveted thereto the vertical web of the angle-bracket 39, the horizontal webs of these brackets overlapping as is clearly indicated in Fig. 4, and being riveted or otherwise secured together as indicated at 41.

Although I have described for purposes of illustration the preferred embodiment of my invention it is to be understood that within the scope of my invention wide deviations may be made therefrom without departing from the spirit of my invention.

20 Claims:

1. A skid having in combination, a floor, a longitudinal girder at each side of said skid, each girder comprising a pair of spaced structural steel members, one at the edge of said floor and both having webs in a horizontal plane, said floor resting on said webs, said girders also each comprising a third structural steel member readily detachable from the girder and positioned above the member at the edge of said floor and forming with said member a channel the open side of which is directed toward the median line of the skid, said floor comprising transverse members the ends of which are received by said channels, and separate wheeled supports for the skid carried at each side thereof near each end of the skid, said supports comprising separate base members rigidly carried by said pairs of structural steel members and acting to hold said members in spaced relation.

2. A skid having, in combination, a pair of longitudinally arranged, transversely spaced, structural steel members at each side of said skid constituting a girder, each member presenting at the upper side thereof a horizontal web, these webs lying in a common horizontal plane, skid supports carried by said members of said girders, cross members resting upon the upper sides of said webs and secured thereto for holding said girders and the longitudinal members constituting each of said girders in spaced relation, transversely arranged floor members resting at opposite ends thereof on the upper sides of said webs, and each of said girders including a structurally-rigid member arranged above the horizontal web of the outer of said pair of members and held in readily detachable, rigid, spaced, assembled relation therewith by means independent of said floor members to form a channel for receiving the ends of said floor members.

3. A skid having in combination, longitudinally arranged girder assemblies at each

side thereof, each comprising a plurality of longitudinally arranged transversely spaced members, transversely arranged flooring carried by said members of said girders, wheeled supports carried by said members of said girders, and a cross member positioned intermediate the length of said skid for holding said girders and the spaced members thereof in spaced relation, said cross member comprising a narrow, vertical flange for retaining said flooring against movement longitudinally of said girders.

4. A skid having in combination, girder assemblies at each side thereof, said girder assemblies including a plurality of longitudinally arranged transversely spaced members and a third member arranged with one of the other members to form a channel for receiving the ends of transversely arranged flooring, wheeled supports carried by the first mentioned members of said girders, and cross members for holding said girders and the spaced members thereof in spaced relation comprising a member positioned intermediate the length of the skid, said member comprising a narrow, vertical flange for retaining said flooring against movement in the channels longitudinally of said girders.

5. A skid having, in combination, girder assemblies at each side thereof, each comprising a plurality of longitudinally arranged angle-irons having at their upper sides horizontal webs in a common horizontal plane, transversely arranged flooring resting upon the upper sides of said webs, wheeled supports carried by said girders, and structural steel cross members positioned intermediate the length of said skid comprising members having horizontal webs resting upon the upper sides of the first mentioned webs and secured thereto for holding said girders and the members thereof in spaced relation, said cross members having vertically positioned webs for retaining said flooring against movement longitudinally of said girders.

6. A skid having, in combination, pairs of longitudinally arranged super-imposed angle-irons positioned at opposite sides of the skid and rigidly held in spaced relation with a web of each horizontally disposed to form channels closed at the edges of the skid by a vertical web of the upper of said angle-irons, said channels opening toward the longitudinal median line of said skid, other longitudinally arranged angle-irons having horizontal webs in the same plane as the lower horizontal webs of the first mentioned angle-irons, transversely disposed brackets carried beneath and by the last mentioned angle irons and the lowermost of each of said pairs of angle-irons, supports for said skid having a base carried by said brackets, transversely arranged members resting upon and secured to said webs in said plane for

holding said angle-irons carrying said brackets in spaced relation, and flooring consisting of flat, transversely arranged members carried at opposite ends in said channels and resting upon the horizontal webs of said angle-irons carrying said brackets.

7. A skid comprising, in combination, separate longitudinal girder assemblies at each side thereof, each assembly comprising a plurality of parallel structural steel members, skid supports carried by each of said girder assemblies near the opposite ends thereof, a floor comprising a plurality of transversely arranged members supported by said girder assemblies, members separate from said members of said girder assemblies and transversely arranged relative to the latter for holding said girder assemblies and said members thereof in spaced relation, structurally-rigid longitudinal members forming with said girder assemblies channels at the outer edge of the skid for receiving the ends of said floor members, and readily detachable spacing means independ-

ent of said floor members holding said longitudinal members in rigid spaced relation to said girder assemblies whereby they form part of the girders.

8. A skid having, in combination, a pair of longitudinally arranged angle irons with a web of each vertically disposed, a floor comprising transversely arranged members resting on the horizontal web of each angle iron, a third angle iron having a horizontally disposed web above the ends of said members of said floor and a vertical web covering the ends of said members, means for securing said third angle iron to the outer angle iron of said pair, oppositely disposed angle irons having vertical webs secured to the vertical webs of said pair of angle irons, and a wheeled support for said skid having a base secured to the horizontal webs of said oppositely disposed angle irons.

In testimony whereof, I have signed my name to this specification.

CLARENCE H. YOUNG.
